UNITED STATES PATENT OFFICE

GEORGE McLEAN WELLS, OF MACOMB, ILLINOIS, ASSIGNOR TO AMERICAN STEEL PRODUCTS CO., OF MACOMB, ILLINOIS, A CORPORATION OF ILLINOIS

CARTON FOR SECTORAL CANOPIES

Application filed March 29, 1929. Serial No. 350,853.

My invention relates to cartons for packing articles of truncated triangular or sector shape. Generally speaking, the objects of my invention are those of providing a single 5 piece folding carton which can be carried in stock in flat sheet form, and which can readily be folded around an article (or stack of articles) of the above mentioned shape for snugly housing the packed article without requiring 10 the use of excelsior or other packing material. Furthermore, my invention aims to provide a carton for this purpose which will include flaps so shaped and arranged that the outer flaps of the carton can readily be secured to 15 each other with gummed tape or the like.

Hollow articles having the shape of a truncated cone—such as brooder hoods or lamp shades—cannot easily or economically be packed in their erected form to avoid damage 20 in transit. Besides, their erected packing requires unduly bulky boxes or crates and involves undesirably high shipping expenses as well as undesirably large space for storing the packed articles.

25 When such articles are constructed in knock-down form and of bendable material, the storage space may be quite small at the factory for the sector-shape parts in their flat form, but the outline of such parts has 30 still made it difficult and expensive to pack them safely for shipment. For example, when inserted in a rectangular carton or a folding box, the shape of such parts will not permit any considerable portion of their 35 edges to fit against the sides of a carton or box.

Consequently, considerable excelsior or other packing must also be wedged into the carton; and with any heavy articles (such as 40 sectional portions of sheet metal brooder hoods) the weight of these articles compresses the packing material when the package is tossed about, thereby often damaging either the carton or the packed articles, or both. 45 Besides, the waste space for the packing involves the use of needlessly large cartons, thereby increasing both the cost of the cartons and the storage space required for the packed goods.

50 My present invention aims to overcome all

of these objections by providing an economically constructed and easily erected carton in which articles of truncated triangular or truncated sector shape can be packed snugly and without requiring excelsior or other 55 packing material.

Illustrative of my invention, Fig. 1 is a plan view of a carton embodying my invention.

Fig. 2 is a section taken along the line 2—2 60 of Fig. 1.

Fig. 3 is a section taken along the line 3—3 of Fig. 1.

Fig. 4 is an enlarged plan view of the same 65 carton with one flap swung open and partially broken away, and with dotted lines showing portions of the upper and lower flaps.

Fig. 5 shows the same carton in its flat forms, together with dotted lines showing the 70 outline of a brooder hood section adapted to be packed in this carton.

In one of its immediate commercial uses, my invention is particularly suited for packing the conical hoods which are commonly 75 used in connection with brooder stoves. Each such hood can be made economically of four counterpart steel sections provided at their edges with perforations for receiving the 80 bolts which unite these sections when the brooder hood is erected, the sections being formed of a grade of flat sheet steel which can be bent manually to the desired curvature. One commercial shape of such a brooder hood sector, as shown in dotted lines in Fig. 5, has 85 upwardly converging edges 1, a downwardly bowed lower edge 2, and an upper edge comprising a downwardly bowed main medial portion 3 disposed between two aligned straight upper end portions 4.

To pack sections of such truncated sector shape, I employ a carton formed of cardboard or other suitable material and of the shape shown in Fig. 5, in which figure certain lines (aside from those outlining the article which is to be packed) indicate the lines along which the carton sheet is to be folded when erecting it.

This carton blank is symmetrical with respect to its medial axis 5 and includes a trun- 100

cated triangular central portion 6 having its upper edge 7 parallel to and spaced from its lower edge 8 by a distance corresponding to the effective height of one of the sectors which are to be packed in the carton. These upper and lower edges 7 and 8 are connected by lateral edges 9 converging upwardly at the same angle as the converging sector edges 1, and the upper edge 7 corresponds in length to the effective width of the top of the truncated sector-shaped article which is to be packed.

Extending outwardly from the four edges of the central blank portion 6 (which affords the bottom of the erected carton) are four rectangular wings of approximately equal width, each wing being of the same length as that edge of the central portion from which it extends; namely, a bottom wing 10, two side wings 11, and a top wing 12. Each of these four wings has a flap extending outwardly from it and of the same basal length as the wing from which it extends.

The bottom flap 13 tapers outwardly at an angle not greater than that of the base angle 14 of the central or bottom portion 6, and this bottom flap may be of relatively short width in proportion to the height of the said central portion 6. The top flap 15 may be rectangular and also is desirably of less width than the difference between the width of the bottom flap 13 and the height (along the axis 5) of the central or bottom portion 6 of the carton blank.

The side flaps 16 each correspond in shape and size to one lateral half of the said bottom portion 6. That is to say, each side flap has right-angled outer corners, has its free outer edge 16A of the same length as the height of the central (bottom) portion 6, has its prospective upper side edge 16B of half the length of the upper edge of the portion 6, and has its other side edge 16C of half the length of the lower edge 8 of the portion 6. With this shaping, the edges 16B and 16C are parallel, and the acute angle 17 between the attached edge of each side flap and the longer side edge of this flap is equal to each of the base angles 14 of the central or bottom carton portion.

When superposed sector-shaped plates are laid on the bottom section 6 as shown in Fig. 5 and the carton is folded up, the side wings 11 extend close to the converging edges of the plates, while the top and bottom wings (12 and 10) respectively engage the upper and lower edges of the plates. The top and bottom flaps (15 and 13) are then folded over the top of the plates as shown in Fig. 3, after which the two side flaps 16 are folded over the top and bottom flaps, thus erecting the carton as shown in Figs. 1, 2, and 3.

Owing to the size and shape of the various portions of the carton, the free end edges 16A of the side flaps then abut against each other, while the adjacent ends 18 of the wings

also closely approach each other. Consequently, the resulting package can readily be sealed by ordinary gummed paper strips—such as a strip 19 overlapping the abutting edges of the two side flaps and extending partially down along the top wing 12 and the bottom wing 10 of the erected carton, and four strips 20 each overlapping the adjacent end portions of two consecutive wings. These strips are shown in dotted lines in Fig. 1, together with short auxiliary strips which may be added to stiffen the longest side of the package. The entire folding and sealing can be done quickly and, owing to the snug embracing of the packed contents, the resulting package will stand rough handling in transit in spite of the weight of its contents.

Since the bends at the scored juncture lines between the various parts of the carton need not be sharp, the width of all four wings (10, 11 and 12) may be uniform in practice. However, with unusually thick material for the carton, the side wings 11 might be slightly wider than the top and bottom wings (12 and 13) so as to allow for the thickness of the latter. So also, the carton might be designed for a little clearance between the converging edges 11 of the sector shaped objects and the side wings 11 of the carton, as indicated in Fig. 5.

However, for object parts of standard size, I preferably construct the carton so that all four of the said wings will fit snugly against the contents of the carton, and in Fig. 5 am only illustrating a slight spacing to avoid a confusion of lines in the drawing. Of course, the carton blank is scored along all of the fold lines and in this flat form occupies very little space. So also, since the score lines and the outer edge portions of the carton blank are all straight lines, the carton is easily manufactured.

When such a carton is used for packing articles of truncated triangular form all four sides of such an article may obviously bear snugly against the four side wings of the carton. With a truncated sector shape for the packed article or articles, it might be assumed that the convex edge of such an article would bulge out the side wing 10 and hence would leave this article free to slide around in the carton, thereby resulting in a possible damage to the carton. However, I have found this to be untrue in practice, for the simple reason that a downward bulging of the bottom wing 10 will effectively shorten the latter, thereby reducing the angle between the side wings 11 and causing these side wings to grip the converging edges of the packed object. Consequently, my carton is equally suitable for use with objects of either truncated triangular shape or of truncated sector shape, and particularly solves the problem of economically packaging articles of truncated sector shaped contour, although I do not

wish to be limited to the uses of my carton or to the particular shape or other details above described.

I claim as my invention:

- 5 1. A foldable carton sheet comprising a laterally symmetrical central portion having upwardly converging side edges and having parallel top and bottom edges, four rectangular wing portions of equal width respectively 70
10 extending outwardly from the four edges of the said central portion and each of the same length as the edge from which it extends, and four flap portions respectively extending from the free edges of 75
15 the wing portions and each having its inner edge of the same length as the wing portion from which it extends; each of the two flap portions connected by wings to the converging edges of the central carton portion corresponding in size and shape to one lateral half 80
20 of the said central portion.
2. A carton for an article having the shape of a truncated sector or triangle formed from a single sheet and comprising a 85
25 carton bottom of truncated triangular form having its side edges diverging at the same angle as the said sector or triangle and its other two edges parallel and spaced by the effective height of the said sector or triangle; 90
30 four upright carton sides respectively connected to the four edges of the said bottom and each of the same length as the edge to which it is connected; and four flaps respectively connected to the outer edges of the said sides 95
35 and each having its connected edge of the same length as the carton side to which it is connected; the flaps connected to the carton sides adjacent to the diverging edges of the carton bottom having a joint configuration and size 100
40 corresponding to that of the said bottom.
3. A carton for an article having the shape of a truncated sector or triangle, formed from a single sheet and comprising: a carton bottom of truncated triangular form having 105
45 its side edges diverging at the same angle as converging edges of the said sector or triangle, the said bottom having its other two edges parallel and spaced by the effective height of the said sector or triangle; four up- 110
50 right carton sides respectively extending from the four edges of the said bottom and each of the same length as the edge of the bottom from which it extends; and four flaps respectively connected to the outer edges of the 115
55 said sides and each having its connected edge of the same length as the carton side to which it is connected; the flaps connected to the carton sides adjacent to the diverging edges of the carton bottom being each of the shape 120
60 and size of one lateral half of the said bottom.
4. A carton for an article having the shape of a truncated sector or triangle, formed from a single sheet and comprising: a carton bottom of truncated triangular form having 125
65
